ADJUSTABLE SUPPORT FOR WINDOW CURTAINS

Filed June 10, 1927

UNITED STATES PATENT OFFICE.

RICHARD C. VOGT, OF WEST NEW YORK, NEW JERSEY.

ADJUSTABLE SUPPORT FOR WINDOW CURTAINS.

Application filed June 10, 1927 Serial No. 197,876.

An object of the present invention is to provide improved curtain-supporting means of the type adapted to be detachably mounted upon a window frame without the use of 5 screws or the like fastening elements.

Another object of the invention is to provide curtain-supporting means of this type adapted to support a plurality of curtains and designed to remain an assembled unit 10 when detached from the window frame, whereby the curtains attached thereto will be held against separation or relative displacement when the supporting means is raised into place or taken down.

Other objects will appear hereinafter.

In the drawings:

Fig. 1 is a front view of the curtain-supporting device showing it mounted upon a window frame;

Fig. 2 a front view of the device removed from the window frame and with the outer curtain rods removed;

Fig. 3 a top plan view of the device upon a larger scale, parts being broken away;

Fig. 4 a fragmentary perspective view of the left hand anchoring and rod-supporting member of the device;

Fig. 5 a rear view of said member;

Fig. 6 a plan view of the right hand anchoring and rod-supporting member;

Fig. 7 a fragmentary perspective view of the right hand portion of the device showing it applied to a window frame;

Fig. 8 a detail rear view of one end of the inner curtain rod; and

Fig. 9 a transverse section taken on the line 9-9 of Fig. 7.

Referring by numerals to the various parts, the curtain-supporting device includes an extensible inner curtain rod 1 comprising two telescoping sections 2 and 3. These sections are made of sheet metal and each is formed with a flat front portion 4 and rearwardly and inwardly turned longitudinal edges 5.

The section 3 slidably receives the section 2 with the flat portion and flanges of the latter in contact with the corresponding parts of the section 2. At its outer end the section 2 has secured to it a flat end member 6 of stiffer metal stock than that of the section. A portion of this end member is inserted into the section, and the flanges of the latter are flattened against the member and indented as at 7 to hold the member rigidly in place.

The projecting portion of the end member is

formed with a vertical slit 8 extending upwardly from its lower edge.

The flat portion 4 of the section 2 is centrally formed upon its inner side with a longitudinal series of spaced depressions 9 formed by pressing the metal of the section outwardly. These depressions are elongated in the direction of the section and each is centrally formed with an aperture 10. Adjacent its inner end, within the section 2, the section 3 is formed with a single aperture adapted to register successively with the apertures 10. Projecting outwardly through said aperture in the section 3 is a locking pin 11. This pin is fixed to a bowed leaf spring disposed within the section 3 and is pressed outwardly by the spring to ride into the depressions 9 and snap into the apertures 10 when the sections are relatively moved. When the pin engages in one of the apertures 10 the sections are rigidly locked against relative movement but may be released by pressing the pin inwardly.

Mounted upon the outer end of the section 3 is an elongated slide 12 made of sheet metal and formed similarly to the section 3 in cross section to provide it with a rear portion 13 opposed to the portion 4 of said section, and with forwardly and inwardly turned flanges 14 which slidably fit around the flanges 5. Secured to the outer end of the slide 12 is an end member 15 similar to the end member 6 and rigidly attached in substantially the same manner. The slide forms in effect a freely shiftable end section for the rod. The member 15 is formed with a vertical slit 16 extending upwardly from its lower edge. The end member 15 is formed with a hook 17, and a hook 18 is also rigidly secured to the inner side of the section 3, adjacent the inner end of the slide 12. A spring 19 and a connected wire strand 20 are anchored to said hooks 17 and 18 respectively. The spring tends to pull the slide 12 inwardly upon the section 3.

To attach the right hand end of the rod 1 to a window frame an anchoring member 21 is provided. This member is made of stiff sheet metal and is formed with a broad, flat, elongated shank 22 and an integral rearwardly turned hook 23 at the outer end of the shank. The hook 23 is formed with two vertically spaced teeth 24 for biting engagement with the side of a window frame or trimming. Rigidly secured to the forward face

of the shank 22 at a point intermediate the ends thereof, and nearer the end having the hook, is a bracket 25 made of stiff sheet metal. This bracket is bent into a substantially U form where it is secured to the shank and extends outwardly to form a short inner arm 26 and a longer outer arm 27. These arms are parallel and extend at right angles to the shank. Secured to the outer or right hand face of the long bracket arm 27 is an outwardly extending bracket arm 28 disposed at right angles to the arm 27 and intermediate the length thereof. The arm 28 is also made of stiff sheet metal and is formed with a foot 29 which is rigidly secured by soldering or otherwise to the arm 27. The bracket arms 26, 27 and 28 are respectively formed with vertical slits 30, 31 and 32 extending downwardly from the upper edges of the arms. The slit 30 is spaced forwardly from the shank 22, the slit 31 is spaced forwardly beyond the end of the arm 26, and the slit 32 is spaced outwardly from the arm 27. The arm 26 is adapted to receive the slotted end member 15 of the slide 12 within the slit 30 to frictionally hold said member and support the right hand end of the curtain rod 1. Secured to the shank 22, adjacent the arm 26 is a bowed leaf spring 33 which is adapted to press against the member 15 and frictionally resist its upward withdrawal from the slit 30.

A similar anchoring member 34 is attached to the end member 6 at the left hand end of the curtain rod and is adapted for biting engagement with the left hand side of the window frame. The member 34 is provided with slotted bracket arms 35, 36 and 37 formed similarly to the arms 30, 31 and 32 respectively and arranged in the same relation to the anchor member. The slotted end member 6 is engaged in the slit in the arm 35 and positively held by a latch 38 in the form of a lever pivoted to the inner face of the arm 35 and formed at one end to close the upper end of the slit. A spring 39 is connected to the other end of the lever and to the member 34 and releasably holds the lever in a position to close the slit.

The bracket arms 27 and 36 at opposite ends of the curtain rod 1 serve as supports for a second curtain rod 40 spaced forwardly from the rod 1 and parallel to it. This second rod is also extensible, being formed of two telescoping sections 41 and 42. At their outer ends these sections are provided with rigid, slotted end members 43 and 44, similar to the members 6 and 15 of the first rod, and adapted to engage their respective arms 36 and 27 and be supported by them in the same manner. A third rod 45 is supported by the bracket arms 37 and 28 in a position spaced forwardly from the rod 40 and parallel to it. The rod 45 is also formed of telescoping sections 46 and 47 to render it extensible. The outer ends of these sections are

bent rearwardly at right angles to the direction of the rods and are provided with rigid slotted end members 48 and 49 similar to the end members of the other rods and adapted to engage their respective bracket arms in the same manner. The telescoping sections of the outer rods 40 and 45 are also made of sheet metal and preferably have a cross sectional form similar to that of the sections of the inner rod 1. The outer rods are however unprovided with locking means and are freely extensible and contractible.

The section 2 of the inner curtain rod has a positive pulling connection with the left hand anchoring member 34 through the slotted end member 6 and the slotted bracket arm 35. The slide 12 also has a positive pulling connection with the right hand anchoring member 22 through the slotted end member 15 and the bracket member 26. The slide however, has a yieldable, resilient pulling connection with the rod section 3 through the spring 19. The spring, therefore, tends to pull the anchoring members toward each other and into biting engagement with the opposite sides of the window frame and firmly support the rods and curtains. The sections of the outer curtain rods also have positive pulling connection with the anchoring members through the connections of their slotted end members 43, 44, 48 and 49 with their respective slotted bracket arms. These outer rods are therefore constrained to extend and contract along with the anchoring members and along with the sections 2 and 3 of the inner rod. The three rods, therefore, always remain in the same relation to each other. There is no relative displacement of either the rods or the curtains thereon and there is no necessity for adjusting any of the rods except the inner one, as the outer rods automatically accommodate themselves to any adjustment of the inner rod.

In the use of the device it may first be approximately adjusted to the width of the window frame by releasing the locking pin 11 of the inner rod and sliding the telescoping sections until said pin locks them in their adjusted positions with the anchor hooks spaced apart a distance less than the width of the window frame. The curtains or other draperies are then placed upon the rods; the rods are mounted upon the anchoring members, and the entire device with the curtains upon it may be lifted as a unit to its proper position upon the window frame. The right hand anchoring member and the sleeve 12 are extended to engage the hooks with the sides of the frame and the spring 19 pulls them into tight engagement with the frame to firmly hold the entire unit in place. It may be readily removed by merely extending the said right hand anchoring member. The rods are so mounted that there is no danger of

their becoming detached when the device is handled as a unit. The various slotted connections frictionally hold the rods against upward displacement and positively hold them against endwise displacement. Either 5 or both of the outer rods may, however, be readily detached from the unit when desired owing to their slip joint connections.

In mounting the device upon a window frame the flat, elongated shanks of the anchoring members are pressed inwardly to bear against the front face of the frame and thus ensure the proper positioning of the rods in parallel relation to the frame. The 10 anchoring members are formed so that the upper tooth of each projects farther than the lower tooth and penetrates more deeply into the window frame. These upper teeth will, therefore, firmly sustain the weight of the device and the curtains and cooperate with the broad flat shanks of the anchoring members to prevent the device from canting downwardly. The connections between the anchoring members and the rods permit the 15 former to rock slightly, as shown in Fig. 6 to accommodate themselves to frames of different shapes. It will be observed that practically all parts of the device are formed of sheet metal, thereby rendering it cheap to 20 manufacture.

What I claim is:

1. A curtain support comprising an extensible curtain rod formed of a pair of sections connected together for relative longitudinal sliding; means to lock said rod sections together in a plurality of relatively adjusted positions; a slide mounted for relative longitudinal movement upon the outer end of one section of said rod; a spring connected to the 30 rod section and to said slide and tending to pull the latter inwardly on the end of the rod; anchoring means formed for biting engagement with one side of a window frame; means detachably connecting said anchoring means to the said slide and forming a positive pull connection therebetween; anchoring means removably attached to the opposite end of the rod to detachably engage the window frame, both anchoring means being formed 40 to support the said rod spaced outwardly from the window frame; and means carried by each anchoring means to support an additional curtain rod.
2. A curtain support comprising an extensible curtain rod formed of a pair of sections connected together for relative longitudinal sliding; means to lock said rod sections together in a plurality of relatively adjusted positions; a slide mounted for longitudinal movement upon one end of said rod; a spring connected to the rod and to said slide and tending to pull the latter inward; an anchor member formed for biting engagement with one side of a window frame; means detachably connecting said anchor member to the 50 slide and forming a positive pull connection therebetween; an anchor member removably attached to the opposite end of the rod to detachably engage the window frame, both anchor members being formed to support an additional curtain rod.
3. A curtain support comprising an extensible curtain rod formed of a pair of sections connected together for relative longitudinal sliding; means to lock said rod sections together in a plurality of relatively adjusted positions; a slide mounted for longitudinal movement upon the outer end of one section of said rod; a spring connected to the rod section and to said slide and tending to pull the latter inwardly on the end of the rod; an anchor member formed with an elongated flat shank to 60 support said additional rods and make positive pull connections with them, whereby said additional rods will be extended or contracted along with the extensible anchor member.
4. A curtain support comprising an extensible curtain rod formed of a pair of sections connected together for relative longitudinal sliding; means to lock said rod sections together in a plurality of relatively adjusted positions; a slide mounted for relative longitudinal movement upon the outer end of one section of said rod; a spring connected to the rod sections and to said slide and tending to pull the latter inwardly on the end of the rod; anchoring means formed for biting engagement with one side of a window frame; means connecting said anchoring means to the said slide and forming a positive pull connection therebetween; and anchoring means attached to the opposite end of the said rod to detachably engage the window frame, both anchoring means being formed to support the 70 said rod spaced outwardly from the window frame.
5. A curtain support comprising an extensible curtain rod formed of a pair of sections connected together for relative longitudinal sliding; means to lock said rod sections together in a plurality of relatively adjusted positions; a slide mounted for longitudinal movement upon the outer end of one section of said rod; a spring connected to the rod section and to said slide and tending to pull the latter inwardly on the end of the rod; an anchor member formed with an elongated flat shank to 80 support said additional rods and make positive pull connections with them, whereby said additional rods will be extended or contracted along with the extensible anchor member.
6. A curtain support comprising an extensible curtain rod formed of a pair of sections connected together for relative longitudinal sliding; means to lock said rod sections together in a plurality of relatively adjusted positions; a slide mounted for longitudinal movement upon the outer end of one section of said rod; a spring connected to the rod section and to said slide and tending to pull the latter inwardly on the end of the rod; anchoring means formed for biting engagement with one side of a window frame; means connecting said anchoring means to the said slide and forming a positive pull connection therebetween; and anchoring means attached to the opposite end of the said rod to detachably engage the window frame, both anchoring means being formed to support the 90 said rod spaced outwardly from the window frame.
7. A curtain support comprising an extensible curtain rod formed of a pair of sections connected together for relative longitudinal sliding; means to lock said rod sections together in a plurality of relatively adjusted positions; a slide mounted for longitudinal movement upon the outer end of one section of said rod; a spring connected to the rod section and to said slide and tending to pull the latter inwardly on the end of the rod; anchoring means formed for biting engagement with one side of a window frame; means connecting said anchoring means to the said slide and forming a positive pull connection therebetween; and anchoring means attached to the opposite end of the said rod to detachably engage the window frame, both anchoring means being formed to support the 100 said rod spaced outwardly from the window frame.
8. A curtain support comprising an extensible curtain rod formed of a pair of sections connected together for relative longitudinal sliding; means to lock said rod sections together in a plurality of relatively adjusted positions; a slide mounted for longitudinal movement upon the outer end of one section of said rod; a spring connected to the rod section and to said slide and tending to pull the latter inwardly on the end of the rod; anchoring means formed for biting engagement with one side of a window frame; means connecting said anchoring means to the said slide and forming a positive pull connection therebetween; and anchoring means attached to the opposite end of the said rod to detachably engage the window frame, both anchoring means being formed to support the 110 said rod spaced outwardly from the window frame.
9. A curtain support comprising an extensible curtain rod formed of a pair of sections connected together for relative longitudinal sliding; means to lock said rod sections together in a plurality of relatively adjusted positions; a slide mounted for longitudinal movement upon the outer end of one section of said rod; a spring connected to the rod section and to said slide and tending to pull the latter inwardly on the end of the rod; anchoring means formed for biting engagement with one side of a window frame; means connecting said anchoring means to the said slide and forming a positive pull connection therebetween; and anchoring means attached to the opposite end of the said rod to detachably engage the window frame, both anchoring means being formed to support the 120 said rod spaced outwardly from the window frame.
10. A curtain support comprising an extensible curtain rod formed of a pair of sections connected together for relative longitudinal sliding; means to lock said rod sections together in a plurality of relatively adjusted positions; a slide mounted for longitudinal movement upon the outer end of one section of said rod; a spring connected to the rod section and to said slide and tending to pull the latter inwardly on the end of the rod; anchoring means formed for biting engagement with one side of a window frame; means connecting said anchoring means to the said slide and forming a positive pull connection therebetween; and anchoring means attached to the opposite end of the said rod to detachably engage the window frame, both anchoring means being formed to support the 130 said rod spaced outwardly from the window frame.

- bear upon the front face of the window frame and with a rearwardly turned hook at the outer end of said shank adapted to engage the side of the window frame; a forwardly extending bracket member carried by the said anchor member; means detachably connecting the outer end of said slide to said bracket member to form a positive pull connection therebetween; an anchor means adapted to be attached to the opposite end of the said rod and formed with an elongated flat shank to bear upon the front face of the window frame and with an integral rearwardly turned hook to engage the side of the said frame; a rigid forwardly extending bracket member carried by the said latter shank; and means detachably connecting the end of said rod to said latter bracket member.
6. A curtain support comprising an extensible curtain rod formed of a pair of sections connected together for relative longitudinal sliding; means to lock said rod sections together in relatively adjusted positions; a slide mounted for longitudinal movement upon the outer end of one section of said rod; a spring connected to the rod section and to said slide and tending to pull the latter inwardly on the end of the rod; an anchor member formed with an elongated flat shank to bear upon the front face of the window frame and with a rearwardly turned hook at the outer end of said anchor member adapted to engage the side of the window frame; a forwardly extending bracket member carried by the said shank; a slip-joint means detachably connecting the outer end of said slide to said bracket member to form a positive pull connection therebetween; an anchor means adapted to be attached by a slip-joint to the opposite end of the said rod and formed with an elongated flat shank to bear upon the front face of the window frame and with an integral rearwardly turned hook to engage the side of the said frame; a rigid forwardly extending bracket member carried by the said latter shank; and means detachably connecting the end of said rod to said latter bracket member.
7. A curtain support comprising an inner extensible curtain rod having a freely sliding end section; a parallel outer extensible curtain rod having a freely sliding end section; a pair of anchoring devices to support the ends of said two rods; means for interlocking the ends of said rods and said anchoring devices whereby the anchoring devices will support said rods and the interlocked extensible ends of the rods will be held to move inwardly and outwardly with the supporting anchoring device; a spring connected to the freely sliding end section of one of the said rods and to the other section of said rod and tending to pull the connected anchoring device and the interlocked extensible end of the other rod longitudinally inward.
8. A curtain support comprising an extensible curtain rod including a pair of sections connected together for longitudinal sliding to vary the length of the rod, means to lock said rod sections together in a plurality of relatively adjusted positions, and a freely slideable end section; a parallel extensible curtain rod having a freely sliding end section; a pair of anchoring devices to engage a window frame and support the ends of said two rods; means for interlocking the ends of the rods and said anchoring devices, whereby the latter will support the rods and the extensible ends thereof will be held to move inwardly and outwardly with the supporting anchoring devices; and spring means connected to one of the rods and acting on the anchoring device connected to the freely slideable end sections and tending to pull said device longitudinally inward.
9. A curtain support comprising an extensible rod formed of a plurality of sections connected together for relative longitudinal sliding to vary the length of the rod; means to lock said rod sections together in a plurality of relatively adjusted positions; an anchoring device connected to one end of said rod to shift longitudinally relatively thereto and detachably engage a window frame; a spring connected to said rod and to said anchoring means and tending to pull the latter longitudinally inward; an anchoring device to detachably connect the opposite end of the rod to the window frame and form a pull connection with the rod; a longitudinally extensible curtain rod; and means detachably connecting the ends of the latter rod to said anchoring device to form positive pull connections with the latter and support it spaced outward parallel to the first rod.
10. A curtain support comprising a pair of sectional longitudinally extensible curtain rods; a pair of anchoring devices to detachably engage a window frame for supporting said rods; means connecting the ends of one rod to said anchoring devices to form pull connections therebetween; spring means tending to relatively pull said devices toward each other and adapt them to be expanded apart to engage window frames of different sizes; and means to detachably connect the ends of the other rod to said anchoring devices to support it spaced parallel to the first rod and form positive pull connections with the devices for expanding with them.
11. A curtain support comprising an inner extensible curtain rod formed of a plurality of sections connected together for relative longitudinal sliding; means to lock said rod sections together in relatively adjusted positions; a slide mounted for longitudinal movement upon one end of the rod; a spring connected to the rod and to said slide and tending to pull the latter inwardly; a pair of anchoring devices for detachably engag-

ing a window frame, connected one to said slide and the other to the opposite end of the rod to form pull connections, one of said devices being detachable to permit the mounting of a curtain upon the rod; an outer extensible curtain rod; and means to support said outer rod parallel to the inner one and form positive pull connections between its ends and

the anchoring devices, one end of the outer rod being detachable from its anchoring device to permit the mounting of a curtain on the rod. ¹⁶

In testimony whereof I hereunto affix my signature.

RICHARD C. VOGT.
